(57) **CLAIM**

The ornamental design for a shoe upper, as shown and described.

DESCRIPTION

FIG. 1 is a rear perspective view of a shoe upper showing our new design;

FIG. 2 is a second rear perspective view thereof;

FIG. 3 is a side view thereof;

FIG. 4 is a second side view thereof; and,

FIG. 5 is a rear view thereof.

The broken lines immediately adjacent to the shaded area represent unclaimed boundaries of the design. The broken lines within the shaded area form no part of the claimed design. The even-length broken lines within the shaded area represent stitching. The broken lines showing the remainder of the shoe are for environmental purposes only and form no part of the claimed design.
